GARMENT DRIER

Filed April 19, 1928

UNITED STATES PATENT OFFICE

JAMES D. SMITH, OF CHARLOTTE, NORTH CAROLINA

GARMENT DRIER

Application filed April 19, 1928. Serial No. 271,278.

My invention relates to a device for cleaning and drying garments without the necessity of wringing them and thus forming creases and wrinkles and tearing the clothes in the wringing operation.

Another object of my invention is to provide a garment drier in which garment cleaners may hasten the drying operation of garments while at the same time holding the garments in open and natural position. Another object of my invention is to provide a garment drier having a plurality of racks over which the garment may be supported and secured with a plurality of motors mounted beneath the racks, said motors being adapted to be swung beneath any rack desired.

Another object of my invention is to provide a garment drier having a base portion in which a motor driven fan is pivoted for a lateral movement with a plurality of racks with garment supporting means associated with said racks, the fan being adapted to be swung on its pivot to its position immediately beneath any one of the plurality of racks.

Some of the objects of my invention having been stated, other objects will appear as the description proceeds, when taken in connection with the accompanying drawings, in which—

Figure 1 is a front perspective view of my garment drier;

Figure 2 is a cross sectional view taken along the line 2—2 in Figure 1;

Figure 3 is an enlarged detail view of one of the means for holding the bottom of the garment.

Referring more particularly to the drawings, the numeral 10 indicates a central standard portion from which projects the members 11, 12, 13, and 14, and secured to the outer ends of these members are the uprights 15, 16, 17, and 18. Circular members 20, 21, 22, and 23 are secured to the member 10 and are also secured to the uprights 15 to 18 and these circular members have the conventional clothes pins 24 secured thereto by means of the tension spring 25.

Pivots mounted on the upright 10 are the supports 26 and 27 which encircle the

member 10 and project outwardly and form a support for the electric motor 28 which motor has the fan 29, secured thereon and around this motor and fan is the circular guard 30 which has the wire screen 31 over the top thereof.

On the other side of the upright 10 are mounted in like manner the braces 32 and 33 which support the motor 34, having the fan 35 thereon and around this motor and fan is the circular rack 36 which has the screen 37 over the top thereof. The motor 28 and associated parts are adapted to be swung selectively under the rack 22 or the rack 23 and the motor 34 and associated parts can likewise be swung under the rack 20 or 21.

The upright 10 projects upwardly and by means of a union 40 is connected to the upright 41 which upright portion 41 has the laterally projecting arms 42, 43, 44, and 45 on which are mounted the pulleys 46 and 47. Secured to the member 41 as at 48 and 49 are the strips 50, 51, 52, and 53 which are secured in such a manner as to leave a space between these strips and the member 41. Slidably secured on the strips 50 to 53 are the members 55, 56, 57, and 58 which members are adapted to receive the end of a cord 59 as at 60 which cord projects upwardly and runs through the pulleys 46 and 47 and has a garment supporting means 61 detachably secured on the lower end thereof. These slidable members 55 to 58 are adapted to be locked in position by the weight of the garment and the tension under which the garment is held as is readily apparent.

In some instances certain articles of apparel such as ladies' dresses, have a double skirt portion and in order to hold both skirt portions, I adjustably secure the ring shaped member 62 to the upright 10 by means of the wing nut 63 and as this member 62 is larger than the members such as 21 and 20, it will fit down over the exterior of said members when not in use and when it is desired to be used it can be raised upwardly and the member 24 secured to the outer skirt and adjusted in position by the wing nut 63.

I also slidably mount on the members 50 to 53 in a manner similar to the mounting

means for the members 55 to 58, the ring shaped members 64 which have the securing means 24 attached thereto and are adapted to hold the sleeve 65 of the garment 66.

5 Slidably mounted around the upright members 15 to 18 is the cuff member 70 in which I adjustably secure the lower end of the upright 71 and this upright 71 passes through the support 72 and has the ring shaped member 73 secured to the upper end thereof and has the securing members mounted thereon.

10 The securing members 24 are adapted to be secured to the sleeves 75 of the garment and these members when slid upwardly or downwardly to the proper position are automatically secured in the proper position by the pull of the garment sleeve exerting a binding effect.

15 20 In operation, I secure a garment to the rack 21 and swing the fan 35 beneath the same, and while this is being operated thus, I can also secure a garment over the rack 20 and have the same ready for drying as soon as the rear 25 garment is dried, at which time the motor and fan can be swung beneath the rack 20 and the drying operation carried on while the rear rack is being cleared of the garment and another garment secured in its stead. This 30 same method of operation can be carried out on the other side of the machine. It is therefore, readily apparent that I can dry two garments at one time, and can be removing other garments from the machine and placing un- 35 dried ones in their stead while the drying operation on the other garments is being carried out.

40 In the drawings and specification I have set forth a preferred embodiment of my invention, and although specific terms are employed, they are used in a generic and descriptive sense only, and not for purposes of limitation, the scope of my invention being set forth in the appended claims.

45 I claim:

1. In a garment drying device for use in cleaning establishments, the combination of a base portion having an extended upright central portion, a plurality of relatively 50 shorter upright portions, a motor driven fan pivotally mounted on the upright central portion, a plurality of circular members secured above the fan and being held in position by the upright central portion and the 55 shorter upright portions, means on the circular members for holding the lower portion of a garment, outwardly projecting members secured to the upper end of the upright central portion, pulleys secured on the outwardly projecting members, a cord adapted 60 to be passed thru the pulleys and to have secured to the outer lower end thereof, a garment supporting member, a plurality of vertically adjustable members slidably mounted 65 on the central upright portion, and means for

holding the sleeves of the garment in proper position.

2. In a garment drying device for use in cleaning establishments, a base portion, an upwardly extending central portion, a fan and fan guard pivotally secured in the base portion to the upwardly extending central portion, means associated with the base portion for holding the lower portion of a garment, means for supporting the upper portion of a garment, and means for holding the sleeves of the garment in proper position. 70 75

3. In a garment drier, a base portion, a central upright portion projecting from the base portion, a plurality of means mounted in the base portion for securing a garment in position, a frame member having a motor driven fan mounted therein, said frame member being pivoted in the base portion and being adapted to be selectively swung into position 80 beneath any of the means for holding the garment. 85

4. In a garment drier, a base portion, an upright portion, a plurality of means for holding a plurality of garments in position 90 for drying at the same time, a motor driven fan member pivotally mounted in the base and being adapted to be selectively placed beneath any of the garment holding means. 95

5. In a garment drier, a plurality of means 100 for holding garments in position while the same are being dried, and a motor driven fan pivotally mounted in the drier and being adapted to be placed in position to dry any selected garment. 105

6. A garment drier having means for holding in proper drying position a plurality of garments at the same time, and a pivotally mounted fan for forcing a column of air thru any selected garment. 110

7. In a garment drier, a base portion, a central upright portion extending above the base portion, a plurality of garment supporting members secured to the upright portion, a plurality of means in the base portion for securing the lower portion of garments in position, a plurality of motor driven fans mounted in the base portion and being pivotally secured therein in such a manner as to permit the fans to be selectively swung into 115 position beneath any of the garment holding means, means for holding the sleeves of the garment during the drying operation, and means for holding a medial portion of the garment during the drying operation. 120

In testimony whereof I affix my signature.

JAMES D. SMITH.
